UNITED STATES PATENT OFFICE

2,677,254

LIQUID COOLER AND DISPENSER

Donald Arenz, Rochester, Minn., and Raymond L. Adolf, Prophetstown, Ill.

Application October 24, 1950, Serial No. 191,796

1 Claim. (Cl. 62—141)

1

The invention relates to an apparatus for cooling liquids and more especially to a mechanically refrigerated cooler.

The primary object of the invention is the provision of an apparatus of this character, wherein beverages, particularly root beer or other liquids, either carbonated or uncarbonated, will pass through a condenser, the latter involving a plurality of cylinders which through tubes connected in series forces the cold condensed liquid from the bottom of a preceding cylinder to the top of a following cylinder and so on forcing from the bottom to the top of the subsequent cylinders until the liquid is in a cooled state, free from unabsorbed carbon dioxide gas.

Another object of the invention is the provision of an apparatus of this character, wherein the condenser has the ability to reduce a foamy frothy mixture to a liquid state in a short period of time and in a relatively small space.

A further object of the invention is the provision of an apparatus of this character, wherein the method of refrigeration, which is a flooded type expansion coil surrounding the condenser cylinders and transfers heat through a conducting medium of either a solid or semi-solid substance, and in this manner the system is free of a sweet water or brine medium of heat transfer, thus being a dry type system.

A still further object of the invention is the provision of an apparatus of this character, wherein the casing having within the condenser and refrigerated coil may be made from any high specific heat and low "K" factor material, such as gypsum cast to form a case or a suitable metal container to hold a molten material, such as tar, asphalt or the like which is poured around the condenser and refrigeration coil within the container, these materials on cooling become congealed into a solid mass, forming an insulation barrier between the refrigerated coils and the outside media but having the inherent characteristics of high specific heat or mass effect which acts to stabilize or hold at an even temperature the liquid being cooled.

A still further object of the invention is the provision of an apparatus of this character, wherein a thermal well imbedded in the conductive mastic between the refrigerated coils and condenser tubes will function so that the cut-out temperature is affected by the refrigerant temperature and cut-in temperature is affected by a slight rise in temperature of the liquid being cooled, thus accurately controlling the temperature of the cooled liquid within the predetermined close limits of the thermostat whose sensitive element is inserted in the said well, this thermostat location being for further assuring a consistent temperature irrespective of flow or time elapse between liquid draws.

A further object of the invention is the provision of an apparatus of this character, which

2

is simple in construction, thoroughly reliable and efficient in operation, automatic in the working thereof, strong, durable, effecting a maximum of refrigeration and cooled liquid capacity in a minimum of space, it being compact, neat in appearance, and inexpensive to manufacture and install.

With these and other objects in view the invention consists in the features of construction, combination and arrangement of parts as will be hereinafter more fully described, illustrated in the accompanying drawings, which disclose the preferred embodiment of the invention, as departures may be made therefrom as properly fall within the scope of the claim hereunto appended.

15 In the accompanying drawings:

Figure 1 is a side elevation of the apparatus constructed in accordance with the invention.

Figure 2 is a top plan view showing the grouped liquid condensers and refrigeration coils within 20 a container, which latter is shown in section.

Figure 3 is a side elevation showing fragmentarily the compressor and electric power unit of the refrigeration system for the apparatus.

Figure 4 is a sectional view taken on the line 25 4—4 of Figure 2 looking in the direction of the arrows.

Figure 5 is a sectional view taken on the line 5—5 of Figure 2 looking in the direction of the arrows.

Figure 6 is a sectional view taken on the line 30 6—6 of Figure 2 looking in the direction of the arrows.

Figure 7 is a sectional view taken on the line 7—7 of Figure 2 looking in the direction of the arrows.

35 Similar reference characters indicate corresponding parts throughout the several views in the drawings.

In order to understand the characteristics of 40 the cooler constituting the present invention, which is primarily designed for cooling root beer it is necessary to set forth the condition of the root beer as it reaches the said cooler, namely, in order to obtain a uniform solution of root beer, it is mixed in predetermined proportions in an open vessel or by any other means, such as proportioning valves. Once having the solution of root beer as above stated, it is drawn into a paddle type carbonator where the root beer solution is carbonated by agitation in a carbon dioxide atmosphere. The root beer after carbonation is a 45 frothy, foamy mixture, relatively warm. Now, the purpose of the present invention is to convert the frothy mixture as it leaves the carbonator into a cold liquid, clear and relatively free of excessive entrained unabsorbed CO₂ gas, and yet during the process of condensing and cooling permits a uniform volume of flow without harsh restrictions which have a tendency to alter the flavor of the 50 finished drink.

55 Referring to the drawings in detail, A designates generally the liquid cooler constituting the pres-

ent invention, which comprises a cabinet 10, preferably of the design illustrated in Figure 1, and constructed from sheet metal, although it may be made from any other suitable material or materials, having at its upper front area a drip or waste-trap or the like 11, the latter confronting a superposed dispensing faucet 12 of any approved type.

Interiorly of the cabinet 10 is arranged a casing 12, it being made from any high specific heat and low "K" factor material, such for example, as gypsum cast to form the casing or a suitable metal container to hold a molten material, such as tar, asphalt and the like, as identified at 13. Within this casing 12 is grouped a series of cylinders 14 which constitutes a condenser which has the ability of reducing a foamy frothy mixture to a liquid state in a short period of time and in a relatively small space as compared for example i. e. to attempting the same result by means of a continuous refrigerated tube which intensively would have to be of a great length.

These cylinders 14, each is capped both at the top and bottom, as at 15, and the series of said cylinders being interconnected by the inlet and outlet tubes 16 and 17, respectively, so that said cylinders are successively filled through the tops by the inlet tubes 16 and successively emptied by the tubes 17. In other words the cylinders are interconnected in series with the inlet tube 16 emptying into the first cylinder, from here the solution is forced by CO₂ pressure from the bottom of the first cylinder to the top of the following cylinder and so in like manner each cylinder is filled at the top and emptied from the bottom through all into the final cylinder, then the solution is forced by pressure from the bottom of the final cylinder which is the outlet of the condenser. The condenser is circuited as heretofore stated to form a trap at the top of each cylinder 14 when the foamy mixture remains above the solid mixture. The liquid is forced from the bottom of the last cylinder and so on until it reaches the final cylinder where the root beer is now becoming liquid. The trap is formed in the top of each cylinder 14 where the unabsorbed CO₂ collects as the root beer remains in the cold surroundings it is reabsorbed into the solution. A purge valve, not shown, has connection at 18 with the last cylinder 14 of the circuit to purge off any excessive CO₂ that is not reabsorbed into the solution.

The solution is piped in its foamy condition in the carbonator, not shown, which receives its supply from any suitable source, the inlet for the piping being indicated at 19, communicating through the top of the first cylinder 14 of the series thereof constituting the condenser, while outlet 20 from the last cylinder 14 of the condenser has connection with a heat exchange, not shown, of any approved type, used for further cooling and retarding the flow of root beer where it flows finally from the faucet 12, which has suitable connection with the heat exchange before mentioned.

Surrounding the condenser involving the cylinders 14 are the expansion refrigerant coils 21, which are wound around the cylinders in groups of three, so that two coils are necessary for six cylinders, and these coils are a part of a refrigeration system of any approved type, only a portion of the same being shown, namely, fragmentarily a compressor 22 and an electric power unit 23 having driving connection 24 with the said compressor. The refrigeration system before men-

tioned is mounted within the cabinet 10 below the condenser and the heat exchange and is of sufficient capacity to assure an outlet temperature of not over 37° when the inlet temperature is not over 55°.

Within the casing 12' a conductive mastic is placed between the copper coils 21 and the cylinders 14, as a means of quick heat transfer, this mastic being heretofore identified at 13, and fills completely the said casing covering said coils and condenser, together with all existing voids, excepting for connections. This fill strata of hydrolene, asphalt or tar having a high specific heat lends hold over of cold to the condenser and at the same time being an insulator holds the cold in the condenser. The mastic cools congealing into a solid mass, forming an insulator barrier between the refrigerated coils and the outside media, but having inherent characteristics of high specific heat or mass effect which acts to stabilize or hold at an even temperature the liquid being cooled.

Embedded in the conductive mastic between the refrigeration coils and the condenser is a thermal well, denoted generally at B, details not shown, of any approved type, electrically re-layed to the electric circuit to the power unit 23, so that the cut-out temperature is affected by the refrigerant temperature and the cut-in temperature is affected by a slight rise in the temperature of the liquid being cooled, which accurately controls the temperature of the cooled liquid within the pre-determined close limits of the thermostat, not shown, whose sensitive element is inserted in the well before mentioned. This above named location of the thermostat further assures a consistent temperature irrespective of flow or time elapsed between liquid draws at the faucet 12 of the apparatus A.

The entire apparatus is self contained and compactly arranged so that a minimum of floor space is required and the construction is such that the drain is conveniently located for receiving all splash, and without extending beyond the lower section of the cabinet which is of the minimum size practicable to accommodate the mechanism of the apparatus, as will be clearly apparent in Figure 1 of the drawings.

What is claimed is:

An apparatus of the kind described, comprising: an enclosure, a container within the enclosure, a series of cylinders intercommunicating with each other within the container forming closed condensers, means interconnecting the cylinders with each other for successively admitting liquid at the uppermost portions thereof from the lowermost portions of succeeding cylinders of the series, means for delivering liquid from a source of supply to the first cylinder of the series, means for dispensing liquid from the last cylinder of the series to the exterior of the enclosure, a refrigeration system within the enclosure having refrigerated coils surrounding the cylinders for cooling liquid within the latter, mastic means filling the container for solid insulation of the cylinders and coils.
